(57) **CLAIM**

The ornamental design for a LED track luminaire, as shown and described.

DESCRIPTION

FIG. 1 is a perspective view of a LED track luminaire in accordance with the present design;

FIG. 2 is a front side view, wherein the rear side view is the mirror image thereof; and,

FIG. 3 is a top view thereof.

The broken lines illustrate portions of the LED track luminaire which form no part of the claimed design. Any shading forms no part of the claimed design and is provided to illustrate contour only and is not an indication of texture, gloss, and the like.
